United States Patent Office.

EDWARD FARNUM, OF BLACKSTONE, MASSACHUSETTS.

Letters Patent No. 61,822, dated February 5, 1867.

IMPROVEMENT IN BUTTER-WORKER.

The Schedule referred to in these Letters Patent and making part of the same.

TO ALL TO WHOM THESE PRESENTS SHALL COME:

Be it known that I, EDWARD FARNUM, of Blackstone, in the county of Worcester, and State of Massachusetts, have invented a new and improved Butter-Worker, and do hereby declare the following to be a full, clear, and exact description thereof, reference being had to the accompanying drawings, making part of this specification, and in which—

Figure 1 is a side elevation.

Figure 2, a vertical and central section; and

Figure 3, a top view or plan.

The object of my present invention is to provide a ready and expeditious means, not only of expelling the butter-milk from a mass of butter, but of thoroughly mixing or incorporating salt therewith.

The invention consists in a vertical box or case open at the top and having a foraminous bottom, together with a receiving drawer or receptacle, and having applied to it and operating within it a plunger in manner and for the purpose as hereinafter described.

In the drawings above mentioned as illustrating my invention, A denotes a rectangular case open at top and having a foraminous partition, *a*, extending across it, a drawer or sliding-box, *b*, being fitted to the interior of the case A and immediately under the partition *a*, or in such manner that the rear side of the drawer, in the act of removing it, shall scrape the under surface of the partition and remove any butter which would otherwise adhere thereto. This drawer *b* has a foraminous bottom and is raised a sufficient distance above the bottom of the case A to allow a pan or vessel, *c*, for receiving butter-milk to be placed under it. A cross-bar, *B*, uniting two standards, *d*, extending upward from or forming part of the sides of the case A, supports in a mortise, *e*, a rod or slider, *f*, fixed to the upper surface of a plunger, *C*, such plunger being of a proper size and shape to fit the interior of the case A. The slider *B* is furcated or formed with a long slot, *g*, for receiving a long lever, *D*, whose fulcrum is a pin, *h*, passing through the rod *f*, as shown in figs. 2 and 3 of the drawings, the base of the fulcrum being a link, *i*, encompassing its end and jointed to the end of the case A.

In operating with the above-described apparatus, a suitable quantity of butter to be worked is placed within the case A and resting upon its foraminous partition *a*. The plunger *C* is then to be inserted in place within the mouth of the case, and resting upon the butter, and the lever *D* to be applied to it. Powerful pressure may now be applied to the butter, the effect of which will be to force it through the foraminous partition *a*, from which it will issue in numerous long cylinders or slivers and be deposited in the drawer *b*, the butter-milk by the same pressure being forced from the mass and through the holes of the partition around the circumference of the slivers of butter into the drawer, from whence it flows through its foraminous bottom into the pan *c*. The butter is thus left in a loose and porous state, highly favorable for receiving the salt which may be spread upon it as it is stirred about, and which by this means will become thoroughly incorporated with it.

I would remark that a number of holes may be made in the slider *f* in order to raise the fulcrum of the lever *D* as the plunger is lowered within the case A while compressing the butter. I would also remark that the base of the lever may be independent of the machine, being attached to the side of a room, for instance, and the machine placed alongside of it.

I claim the improved butter-working machine above described, consisting of the case A, with its foraminous partition *a* and drawer *b*, the plunger *C* and lever *D*, or its equivalent, as and for the purposes set forth.

EDW. FARNUM.
